Patented Apr. 4, 1916.

UNITED STATES PATENT OFFICE.

JAMES H. RITCHIE, OF MADISON, INDIANA.

STOVE-HOOD.

1,178,103.

Specification of Letters Patent. Patented Apr. 4, 1916.

Application filed December 14, 1914. Serial No. 877,181.

To all whom it may concern:

Be it known that I, JAMES H. RITCHIE, a citizen of the United States of America, residing at Madison, in the county of Jefferson and State of Indiana, have invented certain new and useful Improvements in Stove-Hoods, of which the following is a specification, reference being had therein to the accompanying drawing.

- 10 This invention relates to a stove hood and has for its principal object the production of an adjustably mounted hood which is carried above a stove for the purpose of collecting and conveying the vapors and odors from the articles which are being cooked into the stove-pipe whereby the room in which the stove is positioned will not be filled with the odors of the cooking material.
- 15 Another object of this invention is the production of a stove hood which is provided with a resilient bail which is so carried as to normally remain in engagement with the rack for the purpose of supporting the hood at a desired distance above the stove.
- 20 With these and other objects in view this invention consists of certain novel combinations, constructions, and arrangements of parts as will be hereinafter fully described and claimed.

In the accompanying drawing:—Figure 1 is a front elevation of the stove hood illustrating the manner in which the same is used in connection with a stove. Fig. 2 is a side elevation of the stove hood in use. Fig. 3 is a central vertical section through the assembled device. Fig. 4 is a section taken on the line 4—4 of Fig. 3. Fig. 5 is a fragmentary sectional view through a portion of the stove hood illustrating the manner in which the bail is secured thereto. Fig. 6 is a detailed perspective view of the bail.

45 Referring to the accompanying drawing by numerals it will be seen that the device is used in combination with an ordinary stove 1 having the usual stove pipe or flue 2. Inasmuch as the principal object of the invention is the production of a hood which is carried above the stove so as to collect and convey the vapors and steam so as to discharge the same into the stove pipe or flue 2 there is provided an elbow 3 having one end thereof extending into the flue or stove-pipe 2 as shown in Fig. 3. A diagonal

brace 4 is held in engagement with the flue or stove-pipe 2 by means of the rivet 5 and in engagement with the elbow 3 by means of the rivet 6. In this manner, it will be seen that the elbow 3 will be efficiently supported in its correct position. It is of course obvious that a damper 7 having a handle 8 may be rotatably carried by the elbow 3 for the purpose of regulating the draft through the elbow 3 as is necessary.

The elbow 3 extends downwardly for a considerable distance as is clearly shown in Fig. 2 and the tube 9 is telescopically or slidably mounted within the vertical portion of the elbow 3. This tube 9 passes into the interior of the hood 10 and is held in engagement with the hood by means of the solder 11 or in any other suitable manner. This hood 10 may of course be made in any desired shape so as to conform substantially to the general shape of the upper portion of the stove 1. Since this hood is substantially conical, it will collect the vapors and odors adjacent the outer portions of the stove and will cause the same to rise toward its central portion. When the vapors reach this point, they will pass into the tube 9 so as to be discharged into the elbow 3 and then into the stove pipe or flue 2. In this manner it will be seen that the air within the room in which the stove is positioned will be pure and will be free from the odors of cooking inasmuch as the vapors and odors will be easily collected and discharged into the stove pipe or flue 2. In order to retain this stove hood 10 in an adjusted position upon the stove, the elbow 3 is provided with a rack 12, this rack 12 being fixedly secured to the elbow by means of the rivets 13. The teeth of this rack have their outer faces rounded as indicated at 14 while their supporting faces 15 slant inwardly toward the rear supporting back of the rack. The U-shaped bail 16 passes into the hood 10 and is held in engagement with the hood by means of the heads 17. Since the bail 16 is made of a resilient strand of heavy wire, the heads 17 will positively retain the bail in engagement with the hood while the passing of the bail through the hood will tend to swing the bail toward a vertical position inasmuch as the openings through which the bail extends are substantially the same size as the bail and therefore in order to swing the bail outwardly it must be sprung. Consequently as soon as the bail

is released, it will swing toward a vertical position and will therefore normally remain in engagement with the rack 12. If the hood 1 is only a short distance above the stove 1
5 it may be raised by pushing the same upwardly and allowing the tube 9 to move into the elbow 3. Since the outer faces 14 of the teeth of the rack are rounded, the bail will ride over these faces but as soon as the
10 movement of the hood is stopped the bail will spring inwardly so as to engage one of the inner faces 15 of one of the teeth and owing to the downward slant of these faces the bail will be efficiently retained in en-
15 gagement with the rack as shown in Figs. 1 and 3.

From the foregoing description it will be seen that an efficient stove hood has been produced for the purpose of collecting and
20 discharging the obnoxious vapors and which is provided with an efficient bail and rack for the purpose of holding the hood in an adjusted position above the stove without danger of the hood accidentally dropping
25 or being otherwise displaced while in use.

What I claim is:—

In a device of the class described the combination of an elbow, a hood, a tube carried by said hood and extending into
30 said elbow, said tube slidably mounted with-

in said elbow, a rack comprising a body having a plurality of teeth, said teeth having rounded outer faces and downwardly extending inner faces, a U-shaped resilient bail secured to said hood, said bail being 35 adapted to engage said rack for retaining said hood in an adjusted position, said curved faces of said teeth being adapted to allow the hood to be moved upwardly since said bail is adapted to ride over the rounded 40 faces of said teeth, said downwardly extending inner faces being adapted to carry said bail whereby said hood may be retained in an adjusted position said bail having its lower ends extending through 45 said hood, heads forged upon the lower ends of said bail and fitting upon the inner faces of said hood, for supporting the same, the portions of said hood adjacent said bail fitting snugly upon said hood so that, when said bail is urged from a vertical position, the strain on said hood will tend to urge said bail to a vertical position.

In testimony whereof I hereunto affix my signature in presence of two witnesses.

JAMES H. RITCHIE.

Witnesses:

IRA MONTGOMERY,
JOSEPH M. CRAVENS.
